KNOCKDOWN SHIPPING CASE

Hollis W. Blair, North Troy, Vt.

Application September 5, 1934, Serial No. 742,835

3 Claims. (Cl. 217—44)

The invention relates to a shipping case and more especially to a knockdown egg case or drum.

The primary object of the invention is the provision of a case or drum of this character, where-

5 in the body thereof is of cylindrical form and longitudinally split, so that the said body can be flattened for convenience in shipment, particularly for the return of the case or drum to the shipper, and when in collapsed or knockdown condition will be compact and occupy minimum 10 space, the said body being preferably made from wood, such as wood veneer, and materially reinforced to assure strength and rigidity thereto without interference in the knocking down or setting up of the case.

Another object of the invention is the provision 20 of a case or drum of this character, wherein the same will accommodate a filler or fillers for the nesting of eggs therein to assure safety of its contents during shipment, and the end heads constituting a bottom and top are fastened in place in a novel manner to assure security to the contents and also to permit the fitting of these heads and their removal with dispatch.

25 A further object of the invention is the provision of a case or drum of this character, wherein in the end head constituting the bottom for the body is made secure within the latter and such body is externally reinforced to assure maximum strength and to withstand rough handling and usage, as the same is assured of sturdiness and is practically non-breakable.

30 A still further object of the invention is the provision of a case or drum of this character, which is comparatively simple in construction, thoroughly reliable and efficient in its purposes, strong, durable, readily and easily knocked down and set up, and inexpensive to manufacture.

35 With these and other objects in view, the invention consists in the features of construction, combination and arrangement of parts as will be hereinafter more fully described in detail, illustrated in the accompanying drawings, which disclose the preferred embodiment of the invention, 40 and pointed out in the claims hereunto appended.

In the accompanying drawings:

45 Figure 1 is a vertical sectional view through a case or drum constructed in accordance with the invention showing therein fillers for eggs and a dry ice compartment or container, the head being secured with the body of the case.

50 Figure 2 is a sectional view on the line 2—2 of Figure 1 looking in the direction of the arrows.

55 Figure 3 is a fragmentary side elevation of the case or drum.

Figure 4 is an exploded fragmentary elevation showing the interfitting ends of the body and the securing pins for the fastening of the ends together.

Figure 5 is a fragmentary elevation showing 5 the ends of the body interfitted and fastened.

Figure 6 is a sectional view on the line 6—6 of Figure 5.

Figure 7 is an enlarged sectional view on the line 7—7 of Figure 3.

Figure 8 is a fragmentary edge view of the end head constituting the top of the body, showing in detail one part of the fastener therefor.

Figure 9 is a fragmentary side elevation of the body showing the other part of the fastener for 15 the top.

Figure 10 is a fragmentary vertical sectional view looking toward the inner side of the body and showing in detail the fastening of the end head constituting the bottom of the case or drum. 20

Figure 11 is a sectional view on the line 11—11 of Figure 10 looking in the direction of the arrows.

Figure 12 is a view similar to Figure 10 showing a slight modification.

Figure 13 is a sectional view on the line 13—13 25 of Figure 12 looking in the direction of the arrows.

Figure 14 is a view similar to Figure 12 looking toward the other side of the body.

Figure 15 is a sectional view on the line 15—15 of Figure 12 looking in the direction of the arrows. 30

Figure 16 is a fragmentary vertical sectional view through the filler construction for the case or drum.

Figure 17 is a plan view of the body of the case or drum flattened and looking toward the inner 35 side thereof.

Figure 18 is an edge view.

Figure 19 is a plan view of the top of the case or drum.

Figure 20 is a plan view of the bottom for the 40 case or drum.

Similar reference characters indicate corresponding parts throughout the several views in the drawings.

Referring to the drawings in detail, particularly 45 Figures 1 to 11 and 17 to 20 inclusive, the case or drum comprises a one-piece cylindrical body 10, preferably made from wood, such as veneer, and longitudinally split to permit the flattening of the body when it is desired to knock down or collapse 50 the case or drum. This body 10, at the confronting edges to the slit therein, has riveted or otherwise made secure thereto the plates 11 and 12, respectively, the plate 11 being formed with out-struck medially disposed pintle eyes or sleeves 13, 55

while the plate 12 is provided with the slots 14 for accommodating the eyes or sleeves 13 on the interfitting of these plates one with the other. When the plates 11 and 12 are interfitted by the engagement of the pintle eyes or sleeves 13 in the slots 14, the said pintle eyes or sleeves receive a pin-like fastening key 15 which is trained or threaded through the said eyes or sleeves, and in this manner the body 10 is set up in cylindrical form and secure for shipment.

At the bottom edge of the body 10 is a series of cleats 16, each being made from metal straps bent on themselves to straddle the bottom edge of the body 10, with the ends disposed exteriorly and internally of said body and made secure thereto by rivets or other fasteners 17. These cleats 16 constitute rests or bearings for the end head 18 constituting the bottom of the case or drum, it being preferably made from fibrous material and of disk form. The rivets or fasteners 17 carry retaining pieces 19 which hold the bottom 18 at rest upon the cleats 16 when the body 10 is brought to cylindrical form and encircles the said body.

Interiorly of the body 10, at intervals thereof, are longitudinally disposed spaced reinforcing staves or strips 20 which materially strengthen the said body and also form abutments for the bottom 18 and the end head 21 constituting the top of the case or drum.

The top 21 is of disk form and is adapted to rest upon the staves or strips 20 when in place. At intervals of the periphery of the top 21 and made secure thereto are metallic bendable hasps 22, these being engageable with companion eye keepers 23 made secure to the body exteriorly thereof. The hasps 22 are engaged with the keepers 23 when the top has been fitted upon the body in its cylindrical form by the bending of such hasps 22, each being provided with an opening 24 to accommodate the eye portions of the keepers 23. On the engagement of the hasps 22 with the keepers 23 there is passed through the eyes of the keepers 23 a tie wire 25 which encircles the body 10 and is tied, at 26, by the twisting of the ends of the wire together. Thus in this manner the top 21 is made secure to the body.

Carried within the body 10 when set up are the fillers 27 for accommodating the eggs 28 and these fillers are arranged in horizontal rows superposed with relation to each other. Associated centrally with the fillers 27 is a dry ice container 30 for refrigeration purposes.

When the case or drum is to be returned to the shipper, the body 10 is flattened and a plurality of these bodies are stacked one upon the other, while the end heads constituting the bottom 18 and top 21 are placed one upon the other for the stacking thereof and in this fashion are shipped or returned to the shipper, the fillers 27 being destroyed as they are adaptable for single usage.

In Figures 12 to 15 of the drawings there is shown a slight modification of the invention, wherein interfitted cleats 31 and 32, respectively, are cut and stamped from inner and outer hoops or bands 33 and 34, respectively, these being disposed at opposite faces of the body 35. The hoops or bands 33 and 34 are secured in place by headed screws 36, their heads 37 being provided with grooves 38 constituting seats for a tie wire 39, this being located exteriorly of the body and tied correspondingly to the wire 25. The heads 38 of the screws 36 are located exteriorly of the body. It will be noted that the screws 36 carry the retaining

pieces 19 which hold the bottom 18 at rest upon the said interfitted cleats.

By reference to Figure 16 of the drawings it will be noted that the fillers 27, due to the formation of the cups 40 as effected by said fillers, can be interfitted in the respective rows thereof to present a staggered disposition of such cups and thus the capacity of the case for the packing of eggs therein is increased materially because the spaces between the cups in the rows will be occupied by other cups as staggered relative thereto and thus the entire interior space of the case may be occupied.

These fillers are preferably made from pulp and function to cushion the eggs 28 for their safety in shipment in the case or drum.

What is claimed is:

1. A case or drum of the character described comprising a bendable body formed to become flattened or cylindrical shaped, companion plates 20 for interfitting engagement with each other on the body to sustain the latter in cylindrical shape, sleeves on one of the plates and received in slots in the other plate, a fastening key engaging said sleeves on the interfitting of said plates and 25 the sleeves engaged in the slots, end heads of a size to fit within the body in opposite ends thereof, bendable hasps on one of the end heads at diametrically opposite points thereof and overhanging the edge of the body next thereto, keeper 30 eyes on the body and engaged by said hasps, a tie wire insertable in the keeper eyes and made fast about the body, and cleats within the body to form rests for the other head and each made from a single strip bent on itself to straddle the 35 body both interiorly and exteriorly thereof, with these interior and exterior portions made fast to the body, the said head supporting the cleats being inset within said body.

2. A case or drum of the character described 40 comprising a bendable body formed to become flattened or cylindrical shaped, companion plates for interfitting engagement with each other on the body to sustain the latter in cylindrical shape, sleeves on one of the plates and received in slots 45 in the other plate, a fastening key engaging said sleeves on the interfitting of said plates and the sleeves engaged in the slots, end heads of a size to fit within the body in opposite ends thereof, bendable hasps on one of the end heads at dia- 50 metrically opposite points thereof and overhanging the edge of the body next thereto, keeper eyes on the body and engaged by said hasps, a tie wire insertable in the keeper eyes and made fast about the body, cleats within the body to form rests for 55 the other head and each made from a single strip bent on itself to straddle the body both interiorly and exteriorly thereof, with these interior and exterior portions made fast to the body, the said head supporting the cleats being inset within 60 said body, headed fasteners engaging the interior and exterior portions of said cleats for making the same fast to the body and having grooves in their heads, and a tie wire seated in the grooves in the heads of said fasteners and en- 65 circling the body exteriorly thereof.

3. A case or drum of the character described comprising a bendable body formed to become flattened or cylindrical shaped, companion plates for interfitting engagement with each other on 70 the body to sustain the latter in cylindrical shape, sleeves on one of the plates and received in slots in the other plate, a fastening key engaging said sleeves on the interfitting of said plates and the sleeves engaged in the slots, end heads of a size 75

to fit within the body in opposite ends thereof, bendable hasps on one of the end heads at diametrically opposite points thereof and overhanging the edge of the body next thereto, keeper eyes 5 on the body and engaged by said hasps, a tie wire insertable in the keeper eyes and made fast about the body, cleats within the body to form rests for the other head and each made from a single strip bent on itself to straddle the body 10 both interiorly and exteriorly thereof, with these interior and exterior portions made fast to the

body, the said head supporting the cleats being inset within said body, headed fasteners engaging the interior and exterior portions of said cleats for making the same fast to the body and having grooves in their heads, a tie wire seated in the grooves in the heads of said fasteners and encircling the body exteriorly thereof, and ribs longitudinally disposed at intervals on the inner face of the body and constituting abutments for the end heads when within said body. 10
